UNITED STATES PATENT OFFICE.

WESTERN UNDERWOOD, OF LOS ANGELES, CALIFORNIA.

DESIGN FOR A CAPITAL FOR LIGHTING POSTS.

Application filed May 31, 1927. Serial No. 22,248. Term of patent 14 years.

To all whom it may concern:

Be it known that I, WESTERN UNDERWOOD, a citizen of the United States, residing at Los Angeles, in the county of Los Angeles, and State of California, have invented a new, original, and ornamental Design for a Capital for Lighting Posts, of which the following is a specification, reference being had to the accompanying drawing, forming part thereof.

I claim:

The ornamental design for a capital for lighting posts, as shown.

WESTERN UNDERWOOD.
